UNITED STATES PATENT OFFICE.

JOHN F. WILSON, OF NORTH HYDE PARK, VERMONT.

DEVICE FOR CHECKING HORSES.

SPECIFICATION forming part of Letters Patent No. 248,877, dated October 18, 1881.

Application filed July 20, 1881. (Model.)

To all whom it may concern:

Be it known that I, JOHN F. WILSON, of North Hyde Park, in the county of Lamoille and State of Vermont, have invented a new and Improved Device for Checking Horses; and I do hereby declare the following to be a full and exact description of the same, reference being had to the accompanying drawings, forming part of this specification, in which—

10 Figure 1 is a side view of a carriage provided with my invention. Fig. 2 is a bottom-plan view of the same; Fig. 3, a sectional view taken on the line $x-x$, Fig. 2; Fig. 4, a view of the same and fixed collar and devices for connecting them.

15 Similar letters of reference in the several figures denote the same parts.

My invention has for its object to provide improved means for checking horses and preventing them from running away when left to stand; and to this end it consists in a device of novel construction, arranged to operate substantially as I will now proceed to describe.

Referring to the drawings, A represents the 25 floor of the body of a carriage or buggy; B, the springs; C, the rear axle, and D D the wheels. The inner end of the hub of one of the wheels is provided with a gear rim or pinion, E, that is adapted to engage with a smaller pinion, F, 30 on a cross-shaft, G, supported in arms $g-g$, projecting forwardly from the rear axle. Upon this shaft G, between its two supporting-arms, is mounted a drum, H, connected to which is a strap, I, that extends up through a slot, J, 35 in the floor of the body, as shown. The shaft G is capable of a longitudinal or endwise movement to enable its pinion to be thrown into and out of engagement with the pinion E, and the means employed for effecting such longitudinal 40 movement consist of a bell-crank lever, K, pivoted to the innermost of the arms g and loosely connected to the inner end of the shaft G, a connecting-rod, L, and a hand-lever, M, projecting up through the floor of the body and fulcrumed to the same, all as shown in Fig. 2. When the hand-lever is pushed forward the 45 shaft G is moved longitudinally inward, and pinions E and F are thrown out of engagement; but upon the hand-lever being pulled backward the outward movement of the shaft and the engagement of the two pinions take place.

In order to prevent unpleasant rattling of the parts when the shaft is moved inward out of operation, I preferably provide rubber collars or stops N N, fixed to the shaft and adapted to bear against the supporting-arms $g-g$, as shown in Fig. 2. This provision renders the attachment noiseless when not in use.

The operation of the device is as follows: When the vehicle stops, the driver, instead of hitching the horse to a post or other object, ties or otherwise connects the reins to the outer end of the strap I and pulls the handle of the hand-lever so as to throw the pinion F into mesh with the pinion E. This being done 65 the horse can be left to stand alone, and if he attempts to start the turning of the wheels of the vehicle will set the shaft G into rotation and cause the strap I to be wound upon the drum H, and thus draw upon the reins and 70 check the horse. To throw the attachment out of operation the driver has only to shift the lever again, as will be readily understood.

The drum H may be fixed directly to the shaft by a pin or other contrivance, if desired; 75 but I prefer to mount it loosely upon the shaft and to form a recess in its side for the reception of a headed pin, l, and of a spring, l', that is adapted to press said pin outward into one or the other of two or more circular tapering 80 shouldered recesses or grooves, l² l², in the proximate side face of a collar, H', fixed rigidly to the shaft. By this mode of connection, when the vehicle moves forward the shoulder of one or the other of the recesses in the fixed 85 collar engages with the head of the pin l and rotates the drum positively backward; but when the vehicle is backed the pin traverses the slots and clicks past the shoulders, like a pawl, the spring behind it yielding for such 90 purpose, thereby causing the drum to stand still, instead of rotating, while the shaft rotates forward. A pin, m, passing through the shaft outside of the drum, prevents the lateral movement of the latter on the shaft.

The shaft may be adapted to be driven from both wheels of the vehicle, if desired, but ordinarily this will not be found necessary.

Having thus described my invention, what I claim as new is—

The combination of the pinion E on the hub of the carriage-wheel, the longitudinally-mov-

able shaft G, the pinion F on the end of said shaft, the drum H, loosely mounted on the shaft, but prevented from longitudinal movement thereon by a fixed collar, H', having the circular tapered shouldered grooves l^2 l^3 , the headed pin l, and spring l', with the strap leading from the drum up through the floor of the

vehicle, and the means for throwing the shaft into or out of operation, all constructed and arranged substantially as described.

JOHN F. WILSON.
